UNITED STATES PATENT OFFICE.

GUSTAV B. KEIL, OF CHICAGO, ILLINOIS, ASSIGNOR TO FEDERAL ELECTRIC COMPANY,
OF CHICAGO, ILLINOIS, A CORPORATION OF ILLINOIS.

GEARING FOR PORTABLE POWER-TABLES.

1,137,862.

Specification of Letters Patent.

Patented May 4, 1915.

Application filed July 19, 1912. Serial No. 710,477.

To all whom it may concern:

Be it known that I, GUSTAV B. KEIL, a citizen of the United States, and a resident of Chicago, in the county of Cook and State 5 of Illinois, have invented certain new and useful Improvements in Gearing for Portable Power-Tables; and I do hereby declare that the following is a full, clear, and exact description thereof, reference being had to 10 the accompanying drawings, and to the letters of reference marked thereon, which form a part of this specification.

This invention relates to gearing for power tables more particularly intended for 15 use in kitchens of households and the like and consists of the matters hereinafter described and more particularly pointed out in the appended claims.

In the drawings:—Figure 1 is a view representing a front elevation of my improved power table. Fig. 2 is a view representing a horizontal section through the same in a plane indicated by the line 2—2 of Fig. 1. Fig. 3 is a view representing on an enlarged 25 scale, a partial longitudinal section through the top of the table in the plane of the axis of the horizontal shaft supported thereon. Fig. 4 is a view representing a horizontal section through the mechanism supported 30 by the table in a plane indicated by the line 4—4 of Fig. 1. Fig. 5 is a view representing a vertical section through the parts below the table in a plane indicated by the line 5—5 of Fig. 2. Fig. 6 is a view on an enlarged 35 scale representing a partial vertical section through Fig. 4, in a plane indicated by the line 6—6 of Fig. 4. Fig. 7 is a partial perspective view of the lever used for clamping the standard adapted for supporting one end of the horizontal shaft 40 above the power table. Fig. 8 is a perspective view of the base of said standard. Fig. 9 is a view representing a longitudinal section through a coupling provided in the 45 driving shaft, the plane of the section being indicated by the line 9—9 of Fig. 2. Fig. 10 is a view representing a vertical section through Fig. 9 in a plane indicated by the line 10—10 thereof. Fig. 11 is a view representing on an enlarged scale a partial section in a plane indicated by the line 11—11 of Fig. 3. Fig. 12 is a view representing a partial vertical section through Fig. 3 in a plane indicated by the line 12—12 thereof.

55 Referring now to that embodiment of my

invention illustrated in the drawings, 10 indicates a table having four upright legs 11 and top 12. Said table may be of any convenient construction and is preferably made of wood and the top provided with a sheet metal covering 13. The top 13 has an elongated slot, symmetrically located with reference to its sides and ends, to receive a plate 14 which has a marginal horizontal flange 15 let into the table top and a vertical flange 16 which engages against the vertical sides of the slot. 19 indicates an upright tubular bracket having a flat annular base 20 which is bolted to the plate 14. Said bracket has an annular apertured boss 70 or extension 18 below said base engaging within an aperture in the plate 14, said aperture being surrounded by a flange 17 that embraces said boss. A vertical operating shaft 21 has bearing in said bracket. 75 Said bracket is enlarged at its upper end to form gear casings 24, 25, the one above the other, which inclose gears on the vertical operating shaft 21 and on two horizontal auxiliary shafts 27, 29. The bracket is 80 bored centrally to provide bearings for the vertical operating shaft 21 which projects downwardly through the boss 18.

The lateral walls of the gear casings 24, 25 are extended on one side of the bracket 85 to form long bearings 27^a, 29^a, for the respective horizontal shafts 27 and 29. 22, 23 indicate vertically spaced beveled gears fixed to the vertical operating shaft 21, located respectively in the casings 24, 25 and meshing with beveled gears 30, 31 fixed to the horizontal shafts 27, 29. The upper gear casing 25 has a removable cap 32 and the lower gear casing a removable side plate 33, for the purpose of assembly and renewal or 90 removal of the gears.

Each of the shafts 29, 27 has an enlarged end part 32^b forming a radial shoulder which, together with the gear fixed to said shaft in the associated casing, acts to hold 100 the shaft against longitudinal movement. Each enlarged part 32^b of said shafts has a projecting end rib 33^b for engagement in a socket or other suitable coupling device for connecting it to the driven shaft of a rotary 105 operated kitchen utensil or other shaft that may be supported above the table, as will be presently described.

34 indicates a shelf secured to the table legs 11 in any convenient manner and form- 110

ing a support for a motor 35. As shown, said motor is of the electric type, a suitable switch 36 being secured to the table below the top for turning on the electric power 5 when the motor is to be started. The electric connections to the motor are not shown and may be of any usual or familiar kind.

37 indicates the motor shaft which has its axis located in a horizontal plane. Said 0 motor shaft is operatively connected to drive the vertical operating shaft 21 which depends below the table top 12, as heretofore described.

A motor of comparatively low horse 15 power may be used in connection with my improved power table, and in order to use a high speed on said motor and at the same time drive the operating shaft 21 at the low speed required, a speed reducing mechanism 20 is provided in the connection between the motor shaft 37 and the vertical operating shaft 21.

38 indicates a casing supported on the shelf 34 adjacent to the motor. 39 indicates 25 a horizontal shaft having bearing in said casing and provided with a worm 40. The shaft 39 is arranged with its axis in line with the axis of the motor shaft 37 and has fixed to its end adjacent to the motor shaft 30 a disk 41. A similar disk 42 is fixed to the abutting end of the motor shaft 37 and a disk 43 engaged between the disks 41 and 42 is non-rotatively connected to each bolt 43^a which fits into recesses in each face of the 35 disk 43. Said disk 43 is made of material such as leather or the like, capable of providing a slight play between the disks 41 and 42, so that a slight yielding between the disks 41 and 42 is provided to prevent jarring 40 when the motor is first started. One of the disks 41, 42, as shown in the drawings the disk 42 upon the motor shaft, is provided with a groove 42^a in its periphery for the application of a belt when, for example, it 45 is desired to use the motor to drive some mechanism not connected with the table, as a washing machine, or the like.

In the casing 38 adjacent the shaft 39 is 50 rotatably mounted a vertical shaft 45 which has fixed to it a worm-gear 45^a in mesh with the worm 40. The shaft 45 is preferably provided with antifriction bearings, as shown in the drawings (see Fig. 5). Said shaft projects above the top of the casing 55 and has pinned or otherwise rigidly attached to it a coupling member 46 provided with a conical recess 47 in its upper end. The shaft 45 is arranged substantially in vertical alinement below the operating shaft 21 which 60 terminates at a point spaced above it and said shaft 21 has fixed to it a socket member 48 having a conical recess 49 at its lower end. A short shaft 50 connects the two socket members 47, 48, said shaft being provided with pins at its ends which engage

vertical slots formed in the recessed socket members. It is apparent that this construction permits a slight play in the shaft 50 that connects the shaft 45 with the operating shaft 21. This makes exact alinement between the shafts 45 and 21 unnecessary. This construction saves time and labor in assembling the device and also prevents binding of the operating parts in case the motor, worm-gear or casing are slightly displaced with reference to the operating shaft either when shipping the table or by shocks or jars that it may be subjected to when in use.

From this description it is apparent that 80 the rotary movement of the motor-shaft 37 will communicate a rotary movement to the vertical operating shaft 21 and through it to the horizontal auxiliary shafts 27 and 29, at a speed reduced below that of the 85 motor-shaft, so that a motor of high speed but low power may be used to communicate a slow speed of higher power to said auxiliary shafts.

The plate 14 is provided with a longitudinally extending channel 51, the central axis of the same being located in the vertical plane of the horizontal auxiliary shafts 27, 29. The channel is wider at the bottom than at the top, having outwardly inclined side 90 walls 52. Said channel is adapted to receive a base 53 having inclined lateral edges 54 and constituting a support for the shaft to be driven, or in the case of a kitchen utensil, not only of the driving shaft of the same 95 but also of the utensil itself. The channel 51 is made slightly wider than the base 53 so that the latter may be set into the recess from above, and a lever 55 is fulcrumed to swing in a plane parallel to the table top, 100 the same being provided at one end with a cam 56 adapted for engagement with one inclined edge 54 of the base 53. As shown, the said lever consists of a short arm 57 which is fulcrumed in a recess in the plate 110 14 adjacent the channel 51 and of a long arm 58 (see Figs. 6 and 7) which is offset from the first named arm so as to be capable of a swinging movement in a plane below the table top. Said long arm 58 extends through a slot 59 (see Fig. 1) in the frame work of the table. It is apparent from this description that by swinging the lever 55 in one direction the cam end 56 thereof may be brought into forcible engagement with one of the lateral edges 54 of the base 53 so as to force its other inclined edge 54 into close engagement with the opposite overhanging flange or side wall of the channel 52 and thus rigidly lock the base in the position in which it is placed in said channel.

As shown in the drawings, the base 53 has fixed to it an upright standard 60 provided at its upper end with a journal bearing 61 for a horizontal shaft 62. Said bearing

ing is located at such a level above the base 53 that when said base is in place the central axis of the bearing will be in alinement with the central axis of the lower horizontal shaft 27. The shaft 62 is provided with an annular groove 63 within the journal bearing 61 and the bearing has a vertical aperture 64 extending tangentially to said groove, which aperture is adapted to receive a pin 65 that engages within said groove and locks the said shaft 62 in the bearing against longitudinal movement. As shown, the pin 65 has a cap to limit its downward movement and is connected by a chain 66 with the standard 60 to prevent it from being lost.

The inner end of the shaft 62 is connected to the horizontal auxiliary shaft 27 by means of a coupling member 67, the same consisting of a block or plug having recesses 68 at each end provided in the bottom of the recesses with diametric grooves 69. The shaft 62 has a diametric rib 62^a at its inner end similar to the rib 33^x on the horizontal shaft 27, said ribs being adapted to engage in the grooves 69 of the oppositely located recesses 68, when the shaft 62 is locked in the journal bearing 61, as above described. As shown the shaft 62 has fixed to its outer end a pulley 70 for driving connection with a pulley 71 adapted for operating an ice-cream freezer 72 supported in a swinging bracket 73 attached to the shelf 34. Said ice cream freezer is removable from the bracket 73 which may be swung in a familiar manner up into the position indicated by dotted lines in Fig. 1 when the ice cream freezer is not in use and the shaft 62 is wanted for driving other mechanism. Any other device may be operated by the shaft 62 or said shaft may be provided with an emery-wheel or any other tool that it may be desired to use. Instead of the standard 60 and the shaft 62 any rotary driven kitchen utensil having a base 53 like the standard 60 may be used on my power table, as in the case of the power table described in the patent to Goehst and Carpenter, No. 1,032,666, issued July 16th, 1912, the shaft 50 of said rotary driven utensil being coupled to one or the other of the auxiliary shafts

27, 29, depending upon its height above the table, in the same manner as the shaft 62 as herein described.

I claim as my invention:—

55

1. In combination with a power table, a vertical shaft extending above and below said table, a horizontal driven shaft supported below said table, a casing in which said horizontal shaft has bearing, a worm 60 within said casing fixed to said shaft, a vertical shaft having bearing in said casing and located substantially in vertical alinement below said first named vertical shaft, a worm gear fixed to said second named vertical 65 shaft and in mesh with said worm, the adjacent ends of said vertical shafts being spaced apart, a connecting shaft extending between the adjacent ends of said two vertical shafts, and coupling means connecting 70 the ends of said intermediate shafts with each of said vertical shafts, said coupling means permitting angular shifting movement between said intermediate shaft and said two upright shafts.

75

2. In combination with a power table, a rotative driven shaft horizontally supported above said table, a driving shaft, means operatively connecting said driven shaft and said driving shaft, a standard for supporting said driven shaft, said standard having a base, a plate attached to the table below said driven shaft and extending in a plane parallel to said driven shaft, said plate having an elongated channel provided with 80 inclined overhanging side walls and said base having lateral outwardly inclined edges, said base being narrower than said channel, and means for locking said base to said channel comprising a lever fulcrumed 85 to swing in the plane of said channel and having a cam end adapted for engagement with one lateral edge of said base.

In testimony, that I, claim the foregoing as my invention I affix my signature in the 95 presence of two witnesses, this 2nd day of July, A. D. 1912.

GUSTAV B. KEIL.
